MANIFOLD WRITING DEVICE

Horace Drummond Black, Uxbridge, and Christopher Frederick Webb, Eastcote, England, assignors to Bell Punch Company Limited, London, England

Application October 2, 1934, Serial No. 746,553
In Great Britain October 11, 1933

10 Claims. (Cl. 282—16)

This invention concerns improvements in or relating to manifold writing devices of the kind employed for issuing forms such as tickets, bills, receipts or the like upon which certain data 5 can be inscribed before issue by the operator of the device, a copy of the inscribed matter being recorded on one or a plurality of duplicate forms between each of which and the uppermost form, duplicating paper or material is interposed 10 for the purpose of effecting the recording. One or more of the underlying copies is usually retained in the device for the purpose of verifying and/or checking the transactions made through the medium of the form issued from the device. 15 The device comprises a casing for holding a supply of forms and duplicates, and also the necessary feed mechanism for ejecting the forms from the device. An aperture is provided in the casing below which a writing platform is provided over which the forms are arranged to extend prior to the issue thereof from the device and the platform enables the necessary data to be inscribed on the uppermost form through the 20 said aperture in the casing. When the data has been inscribed, the form and perhaps also one or more of the copies thereof are issued from the device by means of the feed mechanism actuated by an operator.

In practice it has been found that should the 25 feed mechanism be operated whilst any pressure is being imparted to the platform, for example, by the point of a pencil or by the operator's finger pressing upon the superimposed form, the movement of the forms may be impeded to such an extent that the forms become jammed or torn in the device and render it inoperable. Again the ejection of the form from the machine may be obstructed accidentally or otherwise and continued operation of the machine jams the form 30 and renders the machine inoperable.

The object of the present invention is to obviate the above disadvantages and to this end a device of the kind referred to is provided with means responsive to pressure imparted to the 35 forms therein or the platform thereof and operable upon such response to render the feed mechanism inoperable.

The invention further comprises a device of the kind referred to wherein a yieldingly dis- 40 placeable member having a normal position and over which the forms are arranged to extend, is so located that pressure imparted thereto causes a displacement of the said member and thereby actuates a locking device for the feed mechanism to maintain the said mechanism locked against operation only so long as the 45 said member is displaced.

Preferably the invention is carried into effect by mounting the platform which supports 50 the forms below the opening in the casing, in

a yielding displaceable manner and providing an operative connection between the platform and a locking pawl in such a manner that displacement of the platform by pressure causes the pawl to move into the path of a movable element, such as teeth of a gear wheel, of the feed mechanism and so prevent the said mechanism from being actuated until the pressure on the platform is released and the pawl thereby withdrawn from the locking position.

In order that the invention may be fully understood, reference is directed to the accompanying diagrammatic drawing, in which:—

Figure 1 illustrates a portion of a manifold writing device embodying the invention, in sectional side elevation, only those parts of the device being shown as are necessary to illustrate the invention, and

Figure 2 is a sectional view on the lines 2—2 of Figure 1.

Referring to the drawing, the device comprises a casing 1 within a lower portion of which (not shown) is stored a supply of forms and duplicates. The forms, indicated at 2 extend together over a feed drum 3, thence below an opening 4 formed in the upper wall of the casing and at least one of the lower forms extends over a guide roller 5 and thence onto a winding drum 6 for record purposes. The uppermost and perhaps one or more of the underlying forms are arranged to be ejected through a slot 7 in the casing 1 as indicated at 8. The drums 3 and 6 and the roller 5 are connected in driving relationship with one another by gearing 9 and form part of a feed mechanism for ejecting the forms, the remainder of the mechanism not being shown as it is unnecessary for enabling the present invention to be understood. Beneath the opening 4 a supporting platform 10 is provided over which the forms are arranged to extend and which provides the rigid 40 surface necessary to enable data to be inscribed upon the uppermost form through the opening 4 and the recording of such data on the duplicates. The platform 10 is hingedly mounted along one side at 11, Figure 2, to the casing 1 and at a point 45 adjacent to its free end bears upon a small button-like projection 12 provided upon a lever 13 which is hinged at 14 to the casing 1 at a point adjacent the button 12. The free end of the lever 13 is arranged to bear against a locking pawl 15 located below the lever and which is pivotally connected at 16 to the casing 1. The nose of the pawl 15 is disposed adjacent to the teeth 9a of the gear wheel of the feed drum 3 and is normally maintained out of engagement therewith by a yielding control in the form of a small spiral spring 17 connected between the pawl and the casing. A stop 18, Figure 2, can be provided to limit the upward movement of the platform 10 and therefore of the lever 13 and the pawl 15.

50 55 60

By the described arrangement it will be appreciated that any downward displacement of the platform is highly magnified by the lever 13 and pawl 15 so that an extremely small displacement 5 is sufficient to bring the nose of the pawl 15 into the locking position with respect to the teeth 9a of the gear wheel of the feed drum and thus lock the said drum and the feed mechanism against operation. The spring 17 can be of a strength 10 such that the device gives an extremely sensitive response to any pressure applied to the platform and thus prevents any actuation of the feed mechanism when pressure is applied to the forms which would otherwise cause the said forms to become 15 jambed or torn in the device and render it inoperative; as soon as the pressure is removed the spring 17 immediately restores the locking pawl and the platform 10 to the normal position in which it leaves the feed mechanism free to be 20 operated.

It will be appreciated that in the event of ejection of a form being obstructed, such form will buckle in its path over the writing platform and this fact will cause pressure upon the platform thus preventing further operation and consequent irretrievable jamming of the machine.

What we claim and desire to secure by Letters Patent of the United States is:—

1. In a manifold writing device comprising a 30 casing and feed mechanism for feeding a plurality of forms and ejecting at least one form therefrom and an opening in said casing presenting an exposed portion of at least one of said forms, the provision of means responsive to pressure imparted through the forms and, operable upon such response to render the feed mechanism for ejecting the forms inoperable.

2. In a manifold writing device comprising a 40 casing and feed mechanism for feeding a plurality of forms and ejecting at least one form therefrom and an opening in said casing presenting an exposed surface of one of said forms, the provision of means responsive to pressure imparted through the forms and operable upon such response to 45 render the feed mechanism for ejecting the forms inoperable only for the duration of such pressure.

3. In a manifold writing device comprising a 50 casing and an opening therein below which a writing platform is located and mechanism for feeding a plurality of forms over said platform past said opening and for ejecting at least one of said forms from the device, the provision of means responsive to pressure imparted to said 55 platform and operable upon such response to render the feed mechanism inoperable.

4. In a manifold writing device comprising a 60 casing and an opening therein below which a writing platform is located and mechanism for feeding a plurality of forms over said platform and for ejecting at least one of said forms from the device, the provision of means responsive to pressure imparted to said platform and operable upon such response to render the feed mechanism 65 inoperable only for the duration of said pressure.

5. In a manifold writing device, the combination 70 of a casing having an opening therein, a writing platform yieldingly displaceable from normal position by pressure applied thereto which is located below said opening and a feed mechanism operable to feed a plurality of forms

over said platform past said opening and to eject at least one of said forms from the device, a locking device responsive to yielding displacements of said platform from normal position and operable upon such response to lock said feed mechanism against operation. 5

6. In a manifold writing device, the combination 10 of a casing having an opening therein, a writing platform yieldingly displaceable from normal position by pressure applied thereto which is located below said opening and a feed mechanism operable to feed a plurality of forms over said platform past said opening and to eject at least one of said forms from the device, and a locking device responsive to yielding displacements of said platform from normal position and operable upon such response to lock said feed mechanism against operation only so long as 15 said platform is displaced.

7. In a manifold writing device, the combination 20 of a casing having an opening therein, a writing platform yieldingly displaceable from normal position by pressure applied thereto which is located below said opening and a feed mechanism operable to feed a plurality of forms 25 over said platform past said opening and to eject at least one of said forms from the device, and a locking pawl operatively connected to said platform and operable to be moved by displacement of said platform from normal position to lock 30 the said feed mechanism against operation during such displacement.

8. In a manifold writing device, the combination 35 of a casing having an opening therein, a writing platform yieldingly displaceable from normal position by pressure thereto which is located below said opening and a feed mechanism operable to feed a plurality of forms over said platform past said opening and to eject at least one of said forms from the device, and a locking pawl operatively connected to said platform by 40 a magnifying lever mechanism and operable upon displacement of said platform from normal position to lock said feed mechanism against operation 45 during said displacement.

9. In a manifold writing device, the combination 50 of a casing having an opening therein, a yieldingly displaceable writing platform located below said opening and a feed mechanism including a gear train, operable to feed a plurality of forms over said platform past said opening and to eject at least one of said forms from the device, and a locking pawl operatively connected to said 55 platform to engage with a tooth of said gear train to lock the feed mechanism against operation only during displacement of said platform.

10. In a manifold writing device, the combination 60 of a casing having an opening therein, a yieldingly displaceable writing platform located below said opening and a feed mechanism including a gear train, operable to feed a plurality of forms over said platform past said opening and to eject at least one of said forms from the device, and a locking pawl operatively connected to said 65 platform by a magnifying lever mechanism and operable upon displacement of said platform to engage with a tooth in said gear train to lock the feed mechanism against operation only during the displacement of said platform.
